CUP OR SIMILAR ARTICLE

William G. Falk, Covington, Ky.

Application October 25, 1951, Serial No. 17,118

Term of patent 7 years

(Cl. D44—9)

To all whom it may concern:

Be it known that I, William G. Falk, a citizen of the United States, and a resident of Covington, in the county of Kenton and the State of Kentucky, have invented a new, original, and ornamental Design for a Cup or Similar Article, of which the following is a specification, reference being made to the accompanying drawing, forming a part thereof.

Fig. 1 is a perspective view of a cup showing my new design.

Fig. 2 is a front elevational view of the cup shown in Fig. 1.

Fig. 3 is a top plan view of said cup.

Fig. 4 is a fragmentary sectional view taken on line 4—4 of Fig. 3.

I claim:

The ornamental design for a cup or similar article, substantially as shown.

WILLIAM G. FALK.
